US00D728947S

(12) **United States Design Patent**
Schweikarth

(10) **Patent No.:** **US D728,947 S**
(45) **Date of Patent:** **** May 12, 2015**

(54) **LOUNGE WITH TABLE**

(71) Applicant: **Kimball International, Inc.**, Jasper, IN (US)

(72) Inventor: **Derek Schweikarth**, Celestine, IN (US)

(73) Assignee: **Kimball International, Inc.**, Jasper, IN (US)

(**) Term: **14 Years**

(21) Appl. No.: **29/491,747**

(22) Filed: **May 23, 2014**

(51) LOC (10) Cl. **06-01**

(52) U.S. Cl.

USPC **D6/336**

(58) **Field of Classification Search**

USPC D6/334-338, 349, 355, 361, 368-370, D6/376, 379-381, 716, 716.1, 716.2, 340, D6/354; 297/16.1, 42, 94, 135, 175, 232, 297/233, 350, 351, 445.1, 448.1, 448.2, 297/451.9; 5/12.1, 12.2

See application file for complete search history.

(57) **CLAIM**

The ornamental design for a lounge with table, as shown.

DESCRIPTION

FIG. 1 is a front perspective view of a design for a lounge with a side table according to a first embodiment, the side table interposed between a pair of adjacent lounges;

FIG. 2 is a front view thereof;

FIG. 3 is a rear view thereof; and

FIG. 4 is a top view thereof.

FIG. 5 is a front perspective view of a design for a lounge with a side table according to a second embodiment, the side table interposed between a pair of adjacent lounges;

FIG. 6 is a front view thereof;

FIG. 7 is a rear view thereof; and

FIG. 8 is a top view thereof.

FIG. 9 is a front perspective view of a design for a lounge with a corner table according to a third embodiment, the corner table interposed between a pair of adjacent lounges;

FIG. 10 is a front view thereof;

FIG. 11 is a rear view thereof; and

FIG. 12 is a top view thereof.

FIG. 13 is a front perspective view of a design for lounge with a corner table according to a fourth embodiment, the corner table interposed between a pair of adjacent lounges;

FIG. 14 is a front view thereof;

FIG. 15 is a rear view thereof; and

FIG. 16 is a top view thereof.

Features shown in broken lines form no part of the claimed designs.

1 Claim, 8 Drawing Sheets
